UNITED STATES PATENT OFFICE.

GEORGE C. MOORE, OF EASTHAMPTON, MASSACHUSETTS, ASSIGNOR OF ONE-HALF TO JOSEPH W. GREEN, JR., OF SAME PLACE.

ELASTIC WOVEN FABRIC.

SPECIFICATION forming part of Letters Patent No. 440,868, dated November 18, 1890.

Application filed May 16, 1890. Serial No. 352,080. (Specimens.)

To all whom it may concern:

Be it known that I, GEORGE C. MOORE, a citizen of the United States, residing at Easthampton, in the county of Hampshire and State of Massachusetts, have invented certain new and useful Improvements in Elastic Woven Fabrics, of which the following is a specification, reference being had therein to the accompanying drawings.

10 In certain classes of elastic fabrics it has been found desirable to have at the edges thereof rubber warps, which are covered by the weft-threads only. These rubber warps at the edges of the fabrics prevent cockling or 15 puckering of the said edges by contracting or drawing up the same uniformly with the central portion of the fabrics. An instance of a fabric of this kind is shown by Patent No. 170,572, to Leonard and Buckley. It has been found, however, in elastic fabrics woven in the manner shown in the said Leonard and Buckley patent, and in which the rubber warps at the edges of the fabrics are covered by the weft only, that the said edge rubber 20 warps are not bound in sufficiently strong to hold them from contracting somewhat when the web is cut into gores.

25 The object of my invention is to provide an elastic fabric with what I term a "double-corded locked rubber edge," and this I accomplish by providing at each edge of the fabric two rubber warp-threads, which in the shedding are alternated relatively to the weft and with each other at successive picks in 30 such a manner as to become so interlocked with the weft that they cannot contract into the web when the latter is cut. These interlocked edge rubber warp-threads are preferably provided with braided fibrous coverings 35 previous to weaving to give the weft a better hold thereon and the better to protect the rubber; but a very good result is also secured by employing two rubber edge warps interlocked, as stated, without the braided coverings.

40 In the accompanying drawings, Figure 1 is a diagrammatical view representing in enlarged cross-section a portion of an elastic fabric embodying my invention. Fig. 2 is a 45 similar view representing the edge rubber warps as being provided with braided cover-

ings. Fig. 3 is a detail view representing a portion of a braid-covered elastic warp.

The fabric represented by Figs. 1 and 2 consists of face warps *a*, back warps *b*, rubber 55 warps *c*, binder-warps *d*, and a weft *e*, as is common in two-ply elastic woven fabrics. At each outer edge of the fabric are two rubber warp-threads *c'*, which in the shedding are alternated relatively to the weft and with 60 each other at successive picks, and which, as is shown in Fig. 1, are covered with the weft only. In the weaving when forming the first shed in the warps the inner rubber warp *c'* will be raised, (as will also be all the rubber 65 warps *c* in the fabric shown;) but the outer rubber warp *c'* will be depressed. After the insertion of the first pick of weft (which will pass under the inner warp *c'* and over the outer warp *c'*) the positions of the two warps 70 *c'* will be reversed relatively to each other or alternated, and when the second pick is inserted it will lie under the outer warp *c'* and over the inner warp *c'*, as shown. The warps *c'* thus become in the fabric alternated relatively to each other and to the successive 75 picks of weft, producing the corded edge shown.

By employing two edge rubber warp-threads and changing them relatively to the weft and 80 to each other at each pick I make a double-corded edge, giving to the fabric a neat finish, and I also interlock these edge rubber warp-threads with the weft so strongly that when the web is cut across in forming gores 85 the said edge rubber warp-threads will not contract within the cut edges. By first incasing these edge rubber warp-threads in braided or other fibrous coverings, as represented in Figs. 2 and 3, the frictional hold of 90 the weft thereon is still further increased and the said edge rubber warp-threads are thus better protected from wear, and any danger of being cut by the weft is also avoided.

I do not intend to limit the use of my invention to the particular form of elastic fabric herein shown, as it is obvious that it may be applied to other or differently-woven elastic fabrics than that herein represented.

I claim—

1. An elastic fabric provided at its edges with two rubber warp-threads alternated with

a weft and with each other at each pick, substantially as set forth.

2. An elastic fabric provided at its edges with two rubber warp-threads incased in fibrous coverings, the said rubber warp-threads being alternated with the weft and with each other at each pick, substantially as set forth.

3. An elastic fabric provided at each of its

outer edges with two rubber warp-threads interlocked by the weft only, substantially as set forth.

In testimony whereof I affix my signature in presence of two witnesses.

GEORGE C. MOORE.
